Primary Examiner — Daniel Bui*Assistant Examiner* — Andrew Kerr(74) *Attorney, Agent, or Firm* — Hudak, Shunk & Farine Co., LPA(57) **CLAIM**

The ornamental design for a “drinking vessel,” as shown and described.

DESCRIPTION

FIG. 1 is a front right side slightly downward-looking perspective view of the drinking vessel showing our new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines in the drawing views represent unclaimed portions of a drinking vessel, which are included for the purpose of illustrating unclaimed environment only, and forms no part of the claimed design.
